UNITED STATES PATENT OFFICE

ROBERT F. BRANCH, OF CHICAGO, ILLINOIS, ASSIGNOR TO W. A. SHEAFFER PEN COMPANY, OF FORT MADISON, IOWA, A CORPORATION OF DELAWARE

DESIGN FOR A DESK STAND

Application filed January 15, 1932. Serial No. 42,494. Term of patent 14 years.

To all whom it may concern:

Be it known that I, ROBERT F. BRANCH, a citizen of the United States, residing at Chicago, in the county of Cook and State of Illinois, have invented a new, original, and ornamental Design for a Desk Stand, of which the following is a specification, reference being had to the accompanying drawings forming a part thereof.

stand embodying my new design comprising an enlarged base portion with a barrel portion extending at substantially right angles to an inclined upper surface thereof, the stand having object supporting portions thereon; and

Fig. 2 is a top plan view of Figure 1.

I claim:

The ornamental design for a desk stand substantially as shown and described.

ROBERT F. BRANCH.
